UNITED STATES PATENT OFFICE.

EUGENE A. DE MAY, OF RICHMOND, TEXAS.

CAR-COUPLING.

SPECIFICATION forming part of Letters Patent No. 375,272, dated December 20, 1887.

Application filed October 11, 1887. Serial No. 252,027. (No model.)

To all whom it may concern:

Be it known that I, EUGENE A. DE MAY, of Richmond, in the county of Fort Bend and State of Texas, have invented certain new and 5 useful Improvements in Automatic Car-Couplings; and I do hereby declare the following to be a full, clear, and exact description of the invention, such as will enable others skilled in the art to which it pertains to make and use 10 it, reference being had to the accompanying drawings, which form part of this specification.

My invention relates to an improvement in automatic car-couplings; and it consists in, 15 first, the combination, with an ordinary pin-and-link draw-head, of a vertically-moving rod or pin and a spring-actuated hook, which is pivoted upon the pin; second, the combination of the draw-head, the hook, a vertically- 20 moving pin, a key or stop for the pin, and an adjustable link connected to the key, whereby the pin can be raised and lowered at the will of the operator; third, the arrangement and combination of parts, which will be more fully 25 described hereinafter.

The object of my invention is to combine with an ordinary pin-and-link draw-head a spring-actuated hook which is automatic in its action and which is connected to the underside of the usual draw-head, whereby either the old style draw-head or an automatic coupling may be used.

Figure 1 is a front view of a coupling embodying my invention. Fig. 2 is a detached 35 perspective showing the parts which constitute my invention. Fig. 3 is a perspective of a coupling-hook. Fig. 4 is a side elevation of a draw-head to which my invention is applied.

A represents an ordinary pin-and-link draw- 40 head, such as is in common use. The pin in this case is formed by the vertically-moving pin B, which passes up through both the coupling-hook C and the head A, as shown, and which has a vertical movement. When this 45 pin B is dropped downward to its full extent, the draw-head is free to have a link inserted; but when the pin is moved upward it closes the mouth of the draw-head the same as a coupling-pin would do if passed down through 50 the top of an ordinary draw-head. This pin B serves both as a coupling-pin and as the

pivot upon which the hook C turns. Passing through or connected to the lower end of this pin B is an arm, stop, key, or pin, D, which extends rearwardly any suitable distance, and 55 to which is connected the coupling-rod E. The upper end of the coupling-rod is fastened loosely to the supporting-link F, which catches over a hook, G, which is screwed or fastened to the end of the car. The coupling-rod E is 60 fastened nearer to one end of the link F than the other, so that if one end of the link is made to catch over the hook G the pin B will be allowed to drop downward far enough to permit a coupling-link to freely enter the draw- 65 head A; but if the opposite end of the link is made to catch over the hook G the pin B will be raised upward through the top of the draw-head, as shown. By simply reversing from one end of the link F to the other upon the 70 hook G the pin is raised and lowered at the will of the operator.

A coupling-hook, C, is pivoted upon the pin, B, and is supported in position against the under side of the draw-head A by means of the flat 75 plate, brace, or support H, which has its rear end fastened to the under side of the draw-head, as shown in Fig. 4. The sleeve I, which is formed upon the inner end of the coupling-hook, and through which the pin B passes, 80 will be made of such a length as will adapt it to high or low cars, and thereby bring the hook to a standard height from the rail. If it is to be applied to a low car, this collar will extend but a very slight distance above the upper edge 85 of the hook; but if it is to be applied to a high car the collar will be made to extend upward sufficiently far to push the hook C downward the desired distance. If the hook is to be applied to a car of medium height, then the collar 90 will be reduced in height, as shown by dotted lines in Fig. 3. The lower end of the collar projects just far enough below the hook to form a flange or bearing-surface, a, which comes in direct contact with the top of the front end of 95 the plate or support H. Formed on the outer side of this hook C is a suitable flange, J, and through this flange is made an opening, in which the inner end of the rod L is hooked. The outer end of this rod is passed through the 100 bracket N, secured to the under side of the corner of the car, and is turned upward, as shown,

so as to form a suitable handle, by means of which the brakemen can operate the hook C while standing to one side of the car, and thus prevent all necessity of the brakemen having 5 to go between the cars, thus endangering both life and limb. Around this rod L is placed a spring, O, of sufficient tension to keep the hook C pressed forward ready to automatically couple with a corresponding hook upon the 10 next adjoining car, and to hold the hook C back out of use when it is not desired that it shall couple when the cars run together. Before the hook C has passed its center of motion the spring serves to force it forward; but after the 15 hook has been drawn backward far enough to pass its center of motion the spring holds the hook back where it will not couple. In order to operate this spring-actuated rod L and hook C either from the platform or the top of the 20 car there is secured to the car at any convenient point a guide, bracket, or plate, P, through which the operating rod or lever Q passes. The lower end of this lever passes through an opening made in the spring-actuated rod L 25 near the coupling-hook, and by moving the upper end of this lever in one direction or the other the hook C can be moved in or out of action, as may be desired. This lever is placed to one side of the center of the car, so as to 30 leave the center of the car free for the brakemen to pass from one car to the other without having to pass around obstructions of any kind.

My invention can be applied to nearly all of 35 the draw-heads now in use upon both freight and passenger cars, for nearly all of them are provided with two bolts to which the plate or support H can be bolted. The hook C will automatically couple a high car to a low one, it being set at a standard height, and it can be 40 uncoupled either from the top, the platform, or either side of the car, as may be desired. As the lever H projects beyond the side of the car the cars can be uncoupled while in motion. Should a car jump the track, the hooks being set at a 45 standard height from the rail, the hook of the derailed car being thrown so much lower than the others, it will automatically uncouple, and thereby free itself from the other car. As the hook C is used in connection with an ordinary draw-head a coupling can be made 50 either to the tender or front bar of the locomotive. When it is desired to remove the parts which constitute my invention from the draw-head A, it is only necessary to partially 55 remove the hook G, when the link F can be re-

moved and allow the pin B to drop out, when the hook C, the spring-actuated lever L, connected thereto, and the operating-rod can be removed, thus leaving no part of my invention in position with the exception of the bracket 60 through which the levers Q L pass and the supporting-plate H.

This coupling will keep the cars at the same distance apart and allow the same slack in a train as the ordinary link, as the only strain on the coupling is in pulling, the draw-head serving as the buffer the same as when the link is used. The hook C being held in close contact with the under side of the draw-head A and the top of the support H, it has no vertical 70 play and there is no chance for the coupling-pin to spring or bend.

Having thus described my invention, I claim—

1. The combination, with a draw-head, of the 75 pin B, the spring-actuated hook C, the connecting-rod, a link, and a hook, substantially as shown.

2. The combination of a link draw-head, with the spring-actuated hook, a support, H, upon 80 the top of which the hook is placed, the pin, the connecting-rod, the link, and the hook, substantially as described.

3. The combination of the link draw-head A, the support H, the hook C, a pivot upon 85 which the hook turns, the spring-actuated rod L, connected to the hook, the rod or lever Q, and suitable guides through which the rods pass, substantially as set forth.

4. The combination, with a pin-and-link 90 coupling-head, of an automatic coupling-hook which is connected to the draw-head, the pin which serves as a pivot for the hook also serving as a coupling-pin for a link, substantially as specified.

5. The combination, with the draw-head A, the hook C, applied directly to its under side and operated by the spring-actuated rod L or lever Q, the support H, secured to the under 95 side of the head, the pin B, which serves both as a coupling-pin and the pivot for the hook, the arm D, connecting-rod E, the link F, and the hook G, substantially as shown and described.

In testimony whereof I affix my signature in 105 presence of two witnesses.

EUGENE A. DE MAY.
